UNITED STATES PATENT OFFICE

153,139

DESIGN FOR A SUIT

Joseph Frumkes, Harrison, N. Y.

Application November 6, 1948, Serial No. 149,511

Term of patent 3½ years

(Cl. D3—4)

To all whom it may concern:

Be it known that I, Joseph Frumkes, a citizen of the United States, a resident of Harrison, New York, have invented a new, original, and ornamental Design for a Suit, of which the following is a specification, reference being had to the accompanying drawing, forming a part thereof.

Fig. 1 is a front elevation of a suit, showing my new design, and Fig. 2 is a rear view thereof.

I claim:

The ornamental design for a suit, as shown.

JOSEPH FRUMKES.
